C. G. MILLER, OF BRATTLEBOROUGH, VERMONT.

Letters Patent No. 88,893, dated April 13, 1869.

IMPROVEMENT IN SAW-FILING MACHINES.

The Schedule referred to in these Letters Patent and making part of the same.

To all whom it may concern:

Be it known that I, C. G. MILLER, of Brattleborough, in the county of Windham, and State of Vermont, have invented a new and useful Improvement in Saw-Filer and Jointer; and I do hereby declare that the following is a full, clear, and exact description thereof, which will enable others skilled in the art to make and use the same, reference being had to the accompanying drawing, forming part of this specification, in which—

Figure 1, Sheet I, represents a plan, or top view of my improved saw-filer and jointer.

Figure 2, Sheet I, is a vertical longitudinal section of the same, taken on the plane of the line $x x$, fig. 1.

Figure 3, Sheet II, is a front elevation, partly in section, of the same.

Figure 4, Sheet II, is a detail longitudinal section of the working-parts of the same, representing them in position for jointing.

Similar letters of reference indicate corresponding parts.

This invention relates to a new apparatus for filing and jointing circular saws, and has for its object to produce an instrument which can be adjusted to all kinds of saws in any suitable position, and for files of suitable length.

The invention consists, first, in so arranging adjustable clamps that files of any desired length can be secured therein, and so that they can be turned at any angle, to suit the shape and position of the saw-teeth.

The invention consists, secondly, in the application of a spring, by which the pivoted frame which holds the file is swung up, so that the file is thus automatically pressed against the saw-tooth.

The invention consists, thirdly, in arranging, on the fixed frame of the instrument, an adjustable sliding frame, for clamping the saw, said adjustable frame serving to clamp saws of all sizes in any desired position.

The invention consists, fourthly, in providing, on the aforesaid fixed frame, for holding the file so that it can slide on the said fixed frame, to enable the file on a pivoted frame to reach to the teeth of large or small saws placed on the same mandrel.

The invention consists, fifthly, in providing a set-screw on the swinging file-frame, and a slotted arm on the sliding support of the same, so that the file-frame can be clamped in any desired position, to have all teeth filed exactly alike, and also to keep the file away from the saw-blade, while the same is being turned.

The invention finally consists in so attaching the file in swivelled extension-holders, that are fitted into a support, swivelled to the frame, which is pivoted to a sliding bed, that the file can be swung on its own axis in any other desired direction, to impart to the cutting-edges of the teeth any desired inclination, or slant.

A, in the drawing, represents a cast-iron, or other

plate, or bed, made in the shape of a cross, or otherwise, so that it will form a firm support for the other part of the machine.

The bed A is provided with a longitudinal groove, a , in which two carriages B and C are fitted, said carriages being provided with set-screws b c , respectively, or with other equivalent devices for clamping them in any desired position to the bed A.

To the front carriage B are pivoted, by a pin, two arms d d , in an inclined direction, said arms having screws e e fitted through their ends, so that they can straddle a saw-blade and clamp the same, as is clearly shown in figs. 2 and 4.

The rear carriage C has projecting lugs, or ears f f , to which, by means of a pin, g , a frame, D, is pivoted.

The frame D projects forward of the lugs, and is held up by a spring, E, which is curved, or L-shaped, and which is fastened to the carriage C with its rear end, as shown.

The front end of the spring is turned up and slotted, and fits against a cross-bar, h , of the frame D, to which it may be secured, by means of a set-screw; i , in any desired position.

When the spring is thus fastened, it will serve to hold up the frame D, and still allow it to be pressed down.

The frame D may, however, be also rigidly locked to the carriage C by means of a set-screw, j , which secures it to a slotted extension, k , of the carriage C, as shown in fig. 2.

The front end of the frame D carries a plate, l , to which, by means of a pin, m , a bar, F, is swivelled, so that said bar can be freely swung on the swivel-pin m . The latter may be made a screw, or may carry a nut, so that the bar can be locked in any desired horizontal or inclined position in front of the frame D.

The bar F has in its front face a dovetail groove, to receive a slotted slide bar, G, which can be freely moved back and forth in the said dovetail groove.

From the ends of the bar G project forward two arms n , o , of which, one, o , is, by a bolt or screw, p , fastened to the slotted bar, so that it can be adjusted on the bar at will.

By thus having one arm o adjustable on the bar G, the distance between the two arms can be varied at will.

On the front end of each arm n , o , is formed a tubular socket, r ; the one on the arm o is, by a screw, or pin, s , pivoted to said arm, so that it can swing thereon. The tube r , on the arm n , however, is fastened to the same by means of a screw, or bolt, t , fitting through a slot of the arm n .

Through each tube r is fitted a swivel-pin, H, which is provided with a handle, u , on the outer, and with a jaw, v , on the inner end.

The file I is fitted with its ends into the jaws v of

the swivel-pins H, and can be of suitable length, as the arm o can be adjusted for that purpose.

By turning the swivel-pins H in the tubes r, the file can be set with its upper surface horizontal, as in fig. 2, or inclined, as in fig. 4, for filing or jointing saws, as may be desired.

By means of screws w w, fitted into the tubes r, the file can be clamped in such position.

The file can also be swung on the pivot s, with the pin t travelling in the slot of the arm n, when the file is to be withdrawn from the saw.

When the bevel of the saw-teeth is to be determined, the bar F is swung on its pivot m, and clamped.

When the apparatus is in operation, the spring E presses the file up against the edge of the saw-teeth, and causes the requisite power to be applied to the file vertically, while the same is being drawn back and forth in the groove-bar F.

The saw is clamped by the screws of the carriage B, which can be adjusted to suit saws of all kinds and sizes. The carriage C can also be adjusted for suiting the position of the saw, and the frame D can be locked in any desired position, either rigidly, by the screw j, or with the spring E, by the screw i.

This apparatus will be of great convenience for filing all kinds of circular saws, and can be attached to the saw-frame so as not to necessitate the removal of the saw for sharpening.

Having thus described my invention,

What I claim as new, and desire to secure by Letters Patent is—

1. The extension-arm o, fitted on the sliding bar G, which has the fixed arm n, in combination with the tube-sockets r on the arms n o, and with the swivel-pins H, for holding the file, all arranged so that a file

of suitable length can be secured, and that the same can be turned on the axis of the pins H, and locked by the screw w, substantially as specified.

2. The spring E, when arranged as described, to keep the frame D elevated, so that it will hold the file against the tooth to be sharpened, as specified.

3. Providing a slot in the spring E, so that it may, by a screw, i, or its equivalent, be locked to the pivoted frame D, substantially as and for the purpose herein shown and described.

4. The jointed sliding frame B, carrying the arms d and clamping-devices e, when arranged longitudinally-adjustable on the fixed bed A, to be adapted to hold saws of all sizes and in suitable positions, as set forth.

5. The sliding frame C, carrying the pivoted frame D, that supports the sliding file-holder, when arranged so that it can be longitudinally adjusted on the bed-plate A, substantially as and for the purpose herein shown and described.

6. The screw j, fitted through the slotted extension k of the carriage C, to lock the file-frame D in any desired position, as specified, for the purpose set forth.

7. The file I, secured, by the swivel-pins H, to the sliding bar G, which works on the swivelled bar F, that is pivoted to the swinging frame D, all arranged as described, to allow the file to be adjusted in every direction, as set forth.

8. The swivelled file-holders H H, when arranged on the arms n o, as described, so that the file can be swung on one fastening-pin, s, while the other, t, travels in the slot of the arm n, as specified.

C. G. MILLER.
